Primary Examiner — Mitchell I. Siegel(74) *Attorney, Agent, or Firm* — K&L Gates LLP(57) **CLAIM**

The ornamental design for a golf club head, as shown and described.

DESCRIPTION

FIG. 1 is a top, front, left side perspective view of a golfing club head showing our new design;

FIG. 2 is a top, front, right side perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a front elevational view thereof;

FIG. 9 is a cross-sectional view taken on line 9-9 of FIG. 5; and,

FIG. 10 is a cross-sectional view taken on line 10-10 of FIG. 5.

The broken lines shown form no part of the claimed design.
